UNITED STATES PATENT OFFICE.

HANS G. JOHNSON, OF WAUKON, IOWA.

WASHING-MACHINE.

SPECIFICATION forming part of Letters Patent No. 605,721, dated June 14, 1898.

Application filed July 10, 1897. Serial No. 644,153. (No model.)

To all whom it may concern:

Be it known that I, HANS G. JOHNSON, a citizen of the United States, residing at Waukon, in the county of Allamakee and State of Iowa, have invented certain new and useful Improvements in Washing-Machines; and I do hereby declare the following to be a full, clear, and exact description of the invention, such as will enable others skilled in the art to which it appertains to make and use the same.

As will be hereinafter fully described and claimed, my invention appertains to washing-machines, and more particularly to that class thereof wherein a combined pumping and agitating process is set up, the object being to utilize the vacuum introduced for the purpose of more thoroughly cleansing the garments treated.

A further object of my invention is to provide a yielding flexible condition for the parts, thus making it unnecessary to always hold the handle in a vertical position, which necessity exists in washing-machines of this character.

In the accompanying drawings, Figure 1 is a vertical section showing my invention ready for use, the handle being partly broken away. Fig. 2 is a bottom plan view of the agitating dasher or disk. Fig. 3 is a horizontal section 30 of Fig. 1, taken on line *a a*.

It may be briefly stated that my invention consists in a hollow chamber or body, the lower end of which is entirely open, the body being preferably conical in section, and, further, of an operating-handle and means for setting up a flexible union between the body and the handle thus provided.

Referring in detail to the several elements, figures will be used to designate the same, 40 the same figure being employed for the same part throughout the views.

In materializing my invention I provide the body 1, which is preferably circular in horizontal section and conical in vertical section, 45 as shown in Figs. 1 and 3. The upper end of the conical body 1 is provided with a central aperture 2, of sufficient diameter to permit the tube 3 to freely move therein and have sufficient lateral play to permit said tube and 50 the handle 4, provided therefor, to be moved in varying angles out of a perpendicular. The tube 3 has attached to its lower end the

agitating-disk 5, provided upon its lower side at proper locations with the reinforcing-ribs 6, the object of which is to reinforce said disk 55 and more reliably hold it in position. Any convenient means for uniting them may be adopted.

In Fig. 2 I have illustrated the ribs 6 as being integrally formed with the collar 7, the latter being designed to encircle the lower end of the tubular socket 3, to which it is reliably attached by screws 8. Near the upper end of the socket 3 I mount in loose union therewith the collar or sleeve 9, held in position 65 by a split key or bolt 10 or other suitable means.

Upon the lower end of the sleeve or collar 9 I form the annular flange 11, designed to prevent the upward movement of the upper 70 end of the coil-spring 12, interposed between said flange and the body. By this interpolation of said spring it will be observed that the tube and handle therefor are normally held at right angles to the plane of the upper 75 surface of the body, though the tension of said spring may be readily overcome when bringing the handle out of the perpendicular or when the body is conforming to the outline 80 of the clothing to be washed.

As previously stated, the tube 3 passes loosely through the aperture 2, and in order to prevent the escape of water upward through said aperture I locate the gasket 13, made of rubber or other suitable yielding material. 85 Said gasket is provided with a central aperture of sufficient size to tightly receive the tube, and as the socket is thereby completely encircled a reliable closure is provided for the aperture 2.

In order to securely seat the gasket 13 in position upon the upper surface of the body and hold it in its operative position, I provide the annular retaining-collar 14, secured to the upper surface of the body in any preferred 95 way, as by screws 15. By the construction above described it will be readily apparent that the handle may be brought out of the perpendicular when the body is raised in a horizontal position, thus permitting the device to 100 be freely operated from any convenient point near the receptacle containing the clothing to be treated.

Having thus described the construction of

my invention, the operation or use may be stated to be as follows: The clothing to be treated is placed in a suitable receptacle in the usual way and the desired quantity of 5 water and other accessories added, when the open end of the body is brought into contact with the clothing and a pressure brought to bear upon the operating-handle 4, which will overcome the tension of the coil-spring 12 and 10 bring the agitating-disk and supporting-ribs into contact with the clothing, while the body 1 will readily conform to the service thereof, thus insuring that all parts thereof will be acted upon and thoroughly cleansed. The 15 act of moving the agitating-disk 5 downward into contact with the clothing tends to create more or less of a vacuum in the body, and apertures 16 are provided in the upper section of the body to overcome this tendency. 20 It will be clearly apparent that by removing the split key or bolt 10 that the collar and operating-handle can be easily removed, permitting the coil-spring to be withdrawn and rendering the interior parts readily accessible 25 for cleansing or other purposes.

While I have described the preferred construction deemed necessary in carrying out my invention, it will be understood that the equivalent thereof is comprehended by me.

Having thus fully described my invention, 30 what I claim as new, and desire to secure by Letters Patent, is—

In a washing-machine, the combination of a body having an aperture in its top, a tube loosely fitting said aperture and having a collar on its upper end and an agitating-disk on its lower end, a coiled spring disposed around the tube and located between said collar and body, a yielding gasket encircling the tube and resting on the upper surface of the body 40 and a plate having an enlarged central aperture and an upturned flange resting on said gasket, all arranged as set forth.

In testimony whereof I affix my signature in presence of two witnesses.

HANS G. JOINSON.
